G. G. FLOYD.
PEDESTAL SIDE FRAME.
APPLICATION FILED JULY 3, 1912.

Patented Dec. 2, 1913.

UNITED STATES PATENT OFFICE.

GEORGE G. FLOYD, OF CHICAGO, ILLINOIS, ASSIGNOR TO AMERICAN STEEL FOUNDRIES, OF NEW YORK, N. Y., A CORPORATION OF NEW JERSEY.

PEDESTAL SIDE FRAME.

1,079,980.

Specification of Letters Patent.

Patented Dec. 2, 1913.

Application filed July 3, 1912. Serial No. 707,433.

To all whom it may concern:

Be it known that I, GEORGE G. FLOYD, a citizen of the United States, residing at Chicago, in the county of Cook and State of Illinois, have invented certain new and useful Improvements in Pedestal Side Frames, of which the following is a specification.

My invention relates to car trucks and has particular reference to a novel side frame 10 and journal box and the means for connecting the two.

It is becoming a well established practice to employ integral cast steel side frames for car trucks these side frames taking the place 15 of the flat plate arch bars which have been employed for many years. It has become a problem in the employment of the one-piece side frame to connect the journal box securely and yet removably thereto. It frequently

20 becomes necessary to remove the car wheels for replacement or turning and at such times it is, of course, necessary to disconnect the journal box from the side frame. In the arch bar truck this was accomplished

25 by removing the journal box bolts and rolling the wheels, axles and journal box out of engagement. The connection formed in such case is, however, unstable particularly in view of the fact that the nuts of the bolts

30 become loose. It has also been suggested to construct jaws on the ends of the integral side frames the journal boxes being fitted between said jaws and being held in place by gravity without reliance upon any bolts.

35 Such construction is shown in prior patents granted to me, Nos. 956,633, and 1,010,034. In such construction the journal box is held against longitudinal and transverse strains by the jaws themselves, there being, however, 40 an emergency connection preventing the separation of the journal box and frame under unusual circumstances.

The present invention is an improvement upon those shown in the patents just mentioned. In this construction I have provided for a slight rocking movement of the frame relative to the box. It has been found in practice that this is conducive to longer life of the associated parts inasmuch as certain 50 strains are eliminated. It will be understood that the roadbed is frequently rough and that one wheel will drop a trifle lower than the other. This tends to rack or distort the truck and if it be a rigid truck will necessarily strain certain parts. It will also

be understood that in casting side frames and journal boxes the dimensions cannot be expected to be absolutely accurate; that is, the molds cannot be made so accurately that any given dimensions will be exactly the same in any two castings. Therefore it is the custom to stipulate, maximum and minimum dimensions for certain parts. For instance, between the jaws of an integral side frame there may be a variation of $\frac{1}{16}$ th to $\frac{1}{16}$ ths of an inch in different castings. The same would hold true in journal boxes. Thus it will be seen that if a journal box of the minimum size is associated with a side frame having the maximum width between jaws, there will be a comparatively large amount of play or clearance. This is undesirable and is obviated by my construction.

The invention will be more readily understood by reference to the accompanying drawings, wherein,

Figure 1 is a side elevation of one form of an integral side frame having pedestal jaws constructed in accordance with my invention; Fig. 2 is a section on the line 2—2 of Fig. 3, and Fig. 3 is a fragmentary enlarged section on the line 3—3 of Fig. 2.

Referring more particularly to the drawings it will be seen that my novel side frame is composed of upper arch bar 10, inverted arch bar 11 and middle portion 12. The upper arch bar 10 is continued and turned downwardly forming a pedestal jaw 13. A bracket 14 is projected from the lower arch bar 11. This bracket serves as one jaw of the pedestal and also provides a bearing surface 15 for a jack or other means for elevating the frame in case the journal box is to be removed. The upper end of the journal box is contracted as at 16, thus providing oppositely disposed wedges or wedge-shaped fillets. A journal box is adapted to be seated in the opening and is provided on its upper wall with inclined surfaces 17, of an angle equal to the angle of the inclinations 16, it being understood, however, that in any case there is a clearance space 18 left between the top wall of the box and the side frame. By this construction it will be seen that the box is securely wedged in place irrespective of the extent of clearance at the sides. Furthermore, the wear incident to service will be taken up and the connection always remain tight. The box is provided on its top and sides with ribs 19. These ribs on the

top wall are substantially the same width as that portion of the side frame corresponding therewith in order that there may be a tight fitting engagement. However, the 5 ribs on the side are slightly flared away from each other and do not normally contact the jaws 13, 14, of the side frame. It will be seen that by this construction a limited rocking movement is permitted thus 10 removing any strain from the side frame due to unevenness in the roadbed.

A lug 20 is provided on the side frame, this lug having a slotted opening there-through. A bolt 21, carried by the lugs 22, 15 on the journal box co-operates with this slotted opening and provides an emergency connection preventing separation of the parts except as desired.

It will be understood that the construction 20 herein shown may be modified to a certain extent and such modifications as are within the scope of my claims I consider within the spirit of my invention.

I claim:

25 1. In a car truck, the combination of a side frame having pedestal jaws, a journal box adapted to be embraced by said jaws, flanges projected from the surface of said box at the top and sides, the flanges on the 30 sides diverging from each other toward the bottom of the box whereby to allow limited rocking movement of the box relative to the side frame, substantially as described.

35 2. In a car truck, the combination of a side frame having integral pedestal jaws, a journal box fitted between said pedestal jaws, flanges on the exterior of said box, said flanges projecting from the top and sides thereof, the top flanges being locked tightly 40 to embrace the side frame and the side flanges being flared from each other where-

by to permit limited rocking movement relative to said frame, substantially as described.

3. In a car truck, the combination of a 45 side frame having jaws providing a journal-box-receiving opening, the upper portion of said opening being contracted transversely, and a journal box adapted to be fitted in said opening and having its upper portion 50 shaped to be wedged in said contracted portion, substantially as described.

4. In a car truck, the combination of a side frame having jaws providing a journal-box-receiving opening, the upper portion of 55 which is contracted to provide wedge surfaces, a journal box fitted in said opening and having its upper portion shaped to be fitted securely within the said wedge surfaces, whereby a tight connection is assured 60 irrespective of the clearance between the jaws and the sides of the box, substantially as described.

5. In a car truck, the combination of a 65 side frame having pedestal jaws, a journal box fitted within said jaws, the contacting surfaces of the box and frame at the top of the box being at an angle whereby the box is wedged in place, substantially as described.

70 6. The combination of a car truck side frame having depending jaws, and a journal box straddled by said jaws, said jaws having upwardly converging faces at opposite sides of the journal box which engage with 75 correspondingly inclined faces on said journal box, substantially as set forth.

GEORGE G. FLOYD.
